UNITED STATES PATENT OFFICE.

VERNON BALFOUR HARLEY-MASON, OF CHEAM, ENGLAND.

STEAM-EXPANSION ENGINE.

1,343,449.

Specification of Letters Patent. Patented June 15, 1920.

Application filed February 21, 1920. Serial No. 360,462.

To all whom it may concern:

Be it known that I, VERNON BALFOUR HARLEY-MASON, a subject of the King of Great Britain, and a resident of Cheam, 5 Surrey, England, have invented certain new and useful Improvements in Steam or like Expansion Engines, of which the following is a specification.

This invention relates to steam or like expansion engines, and has reference particularly to steam engines where steam or other elastic fluid is expanded between a hollow piston and a cylinder cover conforming to the internal contour of the piston. The invention is particularly advantageous in an engine as disclosed in the specifications of Letters Patent Nos. 1,145,391 and 1230617 granted to William Joseph Still, which although an internal combustion engine also 15 operates under steam expanded at the backs 20 of the combustion engine pistons.

In such engines as hitherto constructed it is necessary to provide clearance between the piston and the cylinder cover for the 25 passage of the steam, and although these clearance spaces are small in themselves, the total clearance volume is quite considerable and in many cases amounts to as much as 16% or 20% of the total steam 30 space.

The object of the present invention is to eliminate the clearance space to a large extent and provide for rapid and effective admission and exhaust of the steam. A 35 method of effecting the exhaust of the products of combustion from the cylinder of an internal combustion engine which has been suggested is to provide the edge of the skirt of a hollow piston with teeth so as to form 40 slots which act as exhaust ports and become uncovered when the piston reaches the end of its firing stroke. In no cases, however, has the object of reducing clearance been 45 in view, and moreover the arrangements proposed could not be applied to an engine wherein combustion takes place on one side 50 of the piston and steam expansion on the other. The present invention consists of a particular construction and arrangement 55 of piston and cylinder which results in much reduced steam clearance spaces and renders possible the application of the foregoing method of exhaust to the steam side of engines wherein combustion takes place on one side of the piston and steam expansion

on the other. This particular construction comprises essentially a hollow piston having a piston rod connected to the inner wall of its crown, an inwardly projecting cylinder cover conforming to the internal shape of the piston and having a gland through which the piston rod slides, slots cut or formed in or adjacent the outer edge of the piston skirt, said slots constituting exhaust ports which uncover when 60 the piston approaches the end of its expansion stroke and permit the steam to pass to an exhaust pipe or pipes communicating with the annular passage in which the piston skirt slides in steam tight engagement 65 both with the cylinder wall and cylinder cover.

The invention further comprises the provision of improved means for admitting steam to the interior of the piston, which 70 consists in providing a passage or passages in the piston rod leading to the interior of the piston and coöperating with an inlet port or ports in the cylinder cover, suitably disposed metallic packings being provided 75 through which the piston rod slides.

In the accompanying drawings I have 80 illustrated my invention diagrammatically, Figure 1 being a sectional view of a piston and cylinder cover in its relation with the cylinder, and Fig. 2 is a similar view of a portion of a piston and cylinder cover illustrating the arrangement for introducing steam to the interior of the piston through 85 the piston rod.

Referring to these drawings and particularly to Fig. 1, it will be seen that I provide piston rings 1 between the wall of the cylinder cover 2 and the piston 3, so that the piston skirt 3^a and the cylinder cover maintains steam tight engagement one with the other, and I form the edge of the piston 90 with teeth 5 so that when the expansion stroke finishes, the ports formed between the teeth open to permit exhaust, the arrangement being such that the packing rings never become disengaged. In the drawings the packing rings 1 are shown as fitted to the cylinder cover, which is the preferred arrangement, but it will be appreciated that in some cases this arrangement may be reversed and the packing rings 95 be carried by the piston skirt. The preferred arrangement will be clear upon reference to Fig. 1. The teeth 5 of the piston 100 105 110

may be formed with channels 6 cut behind the piston rings 7 so as to economize in the overall height of the engine.

In Fig. 2 of the drawings I have shown an arrangement wherein the steam is admitted from an inlet port 8^a in the cylinder cover through a port or passage 8 in the piston rod 9, this port being controlled as aforesaid by sliding coöperation with the inlet port 8^a arranged between metallic packings 10, through which the piston rod slides. The foregoing arrangement will be found to possess manifest advantages. In particular the clearance spaces are minimized and in an engine operating also as a combustion engine it is probable that the steam will not become charged with oil to an extent since the time during which the lubricated surfaces are in contact with the steam will be much reduced. Moreover a certain amount of exhaust valve operating gear can be entirely dispensed with.

What I claim and desire to secure by Letters Patent is:

- 25 1. In a steam expansion engine, a cylinder, a hollow piston therein and having a skirt provided with exhaust ports, an inwardly projecting cylinder cover conforming to the internal shape of the piston, an exhaust pipe communicating with the annular space formed between the cylinder and the inwardly projecting portion of the cover, and a piston rod connected to the crown of the piston and sliding through said cover, the said exhaust ports of the piston skirt being uncovered when the piston approaches the end of its expansion stroke and permitting steam to pass through said annular space and to said exhaust pipe.
- 30 2. In a steam expansion engine, a cylinder, a hollow piston therein and having a skirt provided with exhaust ports, an inwardly projecting cylinder cover conforming to the internal shape of the piston, an exhaust pipe communicating with the annular space formed between the cylinder and the inwardly projecting portion of the cover, and a piston rod connected to the crown of the piston and sliding through said cover, the said exhaust ports of the piston skirt being uncovered when the piston approaches the end of its expansion stroke and permitting steam to pass through said annular space and to said exhaust pipe, the skirt of the piston having piston rings near its outer end and also having channels cut behind said rings and forming extensions of the inner ends of said exhaust ports.
- 35 3. In a steam expansion engine, a cylinder, a hollow piston therein and having a skirt provided with exhaust ports, an inwardly projecting cylinder cover conforming to the internal shape of the piston, an exhaust pipe communicating with the annular space formed between the cylinder and the inwardly projecting portion of the cover, and a piston rod connected to the crown of the piston and sliding through said cover, the said exhaust ports of the piston skirt being uncovered when the piston approaches the end of its expansion stroke and permitting steam to pass through said annular space and to said exhaust pipe, the skirt of the piston having piston rings near its outer end and also having channels cut behind said rings and forming extensions of the inner ends of said exhaust ports.
- 40 4. In a steam expansion engine, a cylinder, a hollow piston therein and having a skirt provided with exhaust ports, an inwardly projecting cylinder cover conforming to the internal shape of the piston, an exhaust pipe communicating with the annular space formed between the cylinder and the inwardly projecting portion of the cover, and a piston rod connected to the crown of the piston and sliding through said cover, the said exhaust ports of the piston skirt being uncovered when the piston approaches the end of its expansion stroke and permitting steam to pass through said annular space and to said exhaust pipe, the skirt of the piston having piston rings near its outer end and also having channels cut behind said rings and forming extensions of the inner ends of said exhaust ports.

der, a hollow piston therein and having a skirt provided with exhaust ports, an inwardly projecting cylinder cover conforming to the internal shape of the piston, an exhaust pipe communicating with the annular space formed between the cylinder and the inwardly projecting portion of the cover, and a piston rod connected to the crown of the piston and sliding through said cover, the said exhaust ports of the piston skirt being uncovered when the piston approaches the end of its expansion stroke and permitting steam to pass through said annular space and to said exhaust pipe, said piston rod having a port and a passage leading to the interior of the piston and said cylinder cover having an inlet port to coact with the piston rod port to admit and cut off the supply of steam to the cylinder.

3. In a steam expansion engine, a cylinder, a hollow piston therein and having a skirt provided with exhaust ports, an inwardly projecting cylinder cover conforming to the internal shape of the piston, an exhaust pipe communicating with the annular space formed between the cylinder and the inwardly projecting portion of the cover, and a piston rod connected to the crown of the piston and sliding through said cover, the said exhaust ports of the piston skirt being uncovered when the piston approaches the end of its expansion stroke and permitting steam to pass through said annular space and to said exhaust pipe, the skirt of the piston having piston rings near its outer end and also having channels cut behind said rings and forming extensions of the inner ends of said exhaust ports.

In witness whereof I affix my signature.

VERNON BALFOUR HARLEY-MASON.
